HIRAM M. BURDICK, OF SYRACUSE, NEW YORK, ASSIGNOR TO THE SYRACUSE CHILLED PLOW COMPANY, OF SAME PLACE.

HARROW.

SPECIFICATION forming part of Letters Patent No. 632,777, dated September 12, 1899.

Application filed September 15, 1893. Serial No. 485,563. (No model.)

To all whom it may concern:

Be it known that I, HIRAM M. BURDICK, of Syracuse, in the county of Onondaga, in the State of New York, have invented new and 5 useful Improvements in Harrows, of which the following, taken in connection with the accompanying drawings, is a full, clear, and exact description.

My invention relates to improvements in 10 harrows having adjustable harrow-teeth, and has for its object the production of a simple, practical, and effective device in which the teeth are adjusted a maximum amount with a minimum degree of labor either for varying 15 the position of the teeth or dislodging rubbish; and to this end it consists, essentially, in a draft-frame, teeth carried by the frame, and adjusting means detachably connected to the teeth whereby the teeth are adjusted 20 by said means or are permitted to automatically revolve independently thereof.

The invention furthermore consists in the construction and arrangement of the parts, all as hereinafter more particularly described, 25 and pointed out in the claims.

In describing this invention reference is had to the accompanying drawings, forming a part of this specification, in which like letters indicate corresponding parts in all the views.

30 Figure 1 is a top plan view, partly in section, and Fig. 2 a side elevation of my improved invention, illustrating the general construction and arrangement of its component parts. Fig. 3 is a vertical sectional view taken on line 3 3, Fig. 2. Fig. 4 is a vertical sectional view taken on line 4 4, Fig. 3. Figs. 5 and 6 are respectively vertical section and isometric perspective of one of the adjusting-arms secured to the adjusting-frame for supporting the locking members for engaging the tooth-supports, the corresponding locking member being illustrated by dotted lines at Fig. 5 as in its position assumed when entering the guideway in said arm. Figs. 7, 8, 45 and 9 are respectively isometric perspectives of one of the detached locking members, a tooth-support, and a tooth-clip; and Figs. 10, 11, and 12 are isometric perspectives of the rack secured to the draft-frame for holding in its adjusted position the actuating lever for the adjusting-frame, the connect-

ing-plate secured to the adjusting-frame and provided with a guide for said lever, and the clip-plate for securing said lever to the connecting-plate.

55 It is well known that harrows as at present constructed are usually provided with adjustable harrow-teeth generally so connected together that two or more are adjusted simultaneously. It is equally well known that 60 it is usually desirable to adjust the teeth during the operation of the harrow for regulating the action of the harrow or discharging rubbish and that, although it is comparatively easy during the operation of the harrow to so adjust the teeth as to decrease their amount of penetration, it is practically impossible to force the same more deeply into the soil. My invention is designed to render 65 the adjustment of the teeth to a greater penetration as easy as their withdrawal from the soil and to permit a maximum adjustment 70 of the teeth and discharge of the rubbish with a minimum amount of labor.

The draft-frame A of my invention consists, preferably, of corresponding sections loosely connected or hinged together in the ordinary manner. Each section is formed with openings therein, which are substantially diamond-shaped, and are formed with 80 substantially wedge-shaped rear portions, and each section is preferably composed of zigzag bars a a, having their contiguous portions a' a' suitably secured together.

75 The teeth B are curved or substantially C-shaped and are preferably distributed over the frame in step series across the line of draft and are so arranged that the front bow portions b of teeth in one series are adjacent to the rear soil-working portions b' of teeth 90 in another series for facilitating the discharge of rubbish. The teeth are mounted on supports, presently described, preferably pivoted to the contiguous portions of the frame-bars, and are so constructed and arranged that their 95 front portions are normally at one side of the pivots for said supports or the separate centers around which the teeth B are individually revoluble and their rear soil-working portions b' at the opposite side of said pivots. Said front portions b are nearer to said pivots 100 than the soil-working portions b', whereby as

the tooth-supports swing on their pivots the front portions of the teeth move at greater speed than the rear soil-working portions of the teeth. These teeth may be independently 5 adjustable upon their centers, but are preferably simultaneously adjustable, and their aforesaid arrangement permits said teeth to be adjusted for the purpose of varying their penetration or action or for forming, essentially, 10 rubbish-discharging devices movable through the openings in the frame.

Directly above the draft-frame A is an adjusting-frame C, composed of diagonally-extending bars *c c*, which are connected to the 15 teeth, as presently described, for bracing said teeth and for adjusting the same either to vary the penetration or action of the teeth or to discharge rubbish from the frame.

The tooth-supports D, as best seen at Figs. 20 2, 3, 4, and 8, are formed with central journal-bearings *d* and with extremities projecting above and below the journal-bearings, the upper extremities being each provided with a locking shoulder or shoulders *d'* and the lower 25 extremities with tooth-bearing faces *d²* and with apertures *d³* directly above said faces. The journal-bearing *d* of each tooth-support is mounted upon a hub *e*, projecting from the lower end of a corresponding adjusting-arm 30 E, having its upper end hinged at *e'* to the frame C and its lower end journaled upon a sleeve F, supported upon one extremity of a bolt or clamp *f*, passed through the draft-frame bar or bars *a* for supporting said tooth- 35 support. The clamps or bolts *f* serve both to secure together the contiguous portions of the draft-frame bars *a a* and as pivots for the tooth-supports and the corresponding adjusting-arms for said supports. The front bow 40 portions *b* of the teeth B extend downwardly beneath the draft-frame bars and are arranged beneath the bearing-faces *d²* of the corresponding tooth-supports D. These teeth are secured in operative position by suitable clips 45 G, having separate bearing-faces *g g* arranged beneath the securing ends of the teeth B and having corresponding separate shoulders *g' g'* arranged in cut-outs *d⁴ d⁴* in the lower extremities of the tooth-supports at the bases 50 of the apertures *d³*. Clamps or screws D' are passed through the lower portions of the supports D and the tooth-bearing faces *d²* thereof and bear against the portions of the securing ends of the teeth B interposed between the 55 bearing-faces *g g* of the clips G, and consequently force said clips downwardly and draw their shoulders *g' g'* firmly against the adjacent faces of the supports D and firmly secure the teeth B in operative position. Upon loosening the clamps D' the teeth B are independently adjustable upon their supports in order that the extremities of their soil-working portions may be readily adjusted to the same plane.

65 The tooth-supports D are secured to the adjusting-frame C by locking members H, movable in guideways *e²* in the adjusting-

arms E and provided at corresponding ends with locking shoulders *h*, for engaging the shoulders *d'* of the supports D, and at their 70 other ends with springs *h'*, mounted within the guideways *e²*, for forcing the locking members into operative position with their shoulders *h* in engagement with said shoulders *d'*. The lower ends of the locking members H bear normally against the upper faces or edges of the corresponding frame-bars and are provided with forwardly-projecting shoulders *h²*, the lower faces of which are normally 75 separated from said face or edges of the frame-bars. As the upper ends of the adjusting-arms E are forced forwardly by the movement of the adjusting-frame C, effected as presently described, the forward ends of the shoulders *h²* bear against the adjacent 80 faces or edges of the corresponding frame-bars and automatically disengage the locking shoulders *h* of the locking members H from the tooth-supports and permit the teeth and their supports to move independently of 85 said adjusting-frame C. It is evident, however, that as the locking members are arranged within guides in the adjusting-arms and as the shoulders *h²* bear against the frame-bars said locking members are entirely prevented from derangement during the independent revoluble movement of the teeth and their supports.

Each of the teeth is revoluble upon its individual center or the pivot of its corresponding support; but several of said teeth are preferably partially revolved simultaneously by the adjusting-frame C, previously mentioned. As preferably constructed, all of the teeth upon each section are connected by 105 the adjusting-frame above the draft-frame of said section, and consequently each adjusting-frame is provided with a depending adjusting-arm for each tooth carried by the corresponding section. Each adjusting-frame 110 C is operated by an actuating-lever C', arranged, preferably, at the rear of said frame and having its upper end provided with a suitable hand-engaging portion and its lower end pivoted upon a suitable support, as a 115 sleeve C², mounted upon one end of a clamp or bolt, for supporting one of the tooth-supports. The levers C' are engaged by substantially parallel shoulders C², formed upon connecting-plates C³, Figs. 2, 3, and 11, hinged 120 at C⁴ to the adjusting-frames C C, for flexibly or loosely connecting said levers to said frames. A suitable clip-plate C⁵, Figs. 2, 3, and 12, is secured to the outer face of each of the levers C' by the pivotal pin C⁴ for the 125 corresponding connecting-plate C³, and is provided with shoulders C⁶, bearing against one edge of the plate C³. Arranged in proximity to each of the levers C' is a rack C⁷, rigidly secured to the frame by suitable fastening means, as one end of the clamp f, supporting the corresponding lever C', and a clamp C⁸, engaged with a frame-bar adjacent to the bar provided with said clamp or bolt f.

The levers C' are provided with locking members C⁹, movable in a guide C¹⁰ in the plate C³, and are provided with hand-engaging levers C¹¹, connected to said locking members by links or spring-bars C¹². Suitable springs C¹³ are mounted upon the lower ends of the links C¹² and operate to normally force the locking members C⁹ into operative position for engaging the teeth of the racks C⁷ and holding the levers C' C' in their adjusted position. When the teeth are arranged so as to penetrate to the maximum degree into the soil and to be held in said position by the adjusting-frame, the locking members of the actuating-levers are engaged with the rear shoulders of the stationary racks secured to the draft-frame, and as it is desired to decrease the penetration of said teeth the hand-levers C¹¹ are operated to withdraw the locking members C⁹ and the levers C' are shifted forwardly until the locking members C⁹ are engaged with the front shoulders of said racks. This movement of the levers C' C' and the withdrawal from the soil of the digging portions of the teeth is readily effected while the harrow is in operation, as the draft of the harrow aids the operator in securing said adjustment. On the contrary, if the operator desires while the harrow is in motion to increase the amount of penetration of the digging portions of the teeth he is obliged to overcome the upward tendency of the rear ends of the teeth caused by the draft of the harrow, and such an operation is well nigh impossible. My harrow, however, permits of this adjustment, since as the levers C' C' are moved forwardly, so that their locking members are forced beyond the shoulders of the racks C⁷ C⁷, the locking members of the adjusting-arms normally in engagement with the tooth-supports are automatically forced from operative position, and the harrow then rides upon the front bow portions of the teeth, which by the draft of the harrow are automatically rolled or revolved beneath the draft-frame, and the teeth when completely revolved are then in their position assumed when penetrating to the utmost extent within the soil and are by the draft of the harrow automatically drawn into the soil. After the locking shoulders d' of the tooth-supports have passed beyond the shoulders of the locking members normally engaged with said tooth-support shoulders and as the teeth are automatically revolving beneath the frame, the operator retracts the actuating-levers C' C' and the locking shoulders d' of said tooth-supports automatically move upward and engage with the locking shoulders of the locking members H. The operator is then free to again move the levers C' C' forwardly and decrease the amount of penetration of the digging portions of the harrow-teeth B. It is thus evident that my peculiar construction of harrow permits of a maximum degree of adjustment of the harrow-teeth with a minimum degree of labor.

The operation of my invention will be readily perceived from the foregoing description and upon reference to the drawings, and it will be particularly noted that the teeth are independently adjustable in their respective supports, and that these supports are simultaneously adjusted for varying the position of the teeth or discharging rubbish from the frame, and are permitted to automatically revolve independently of the adjusting means, and that the harrow is simple in construction, readily assembled, and is durable and effective in use.

The described constructions of draft-frame, harrow-teeth, and the supports for said teeth are particularly applicable for use with the described construction of adjusting means for adjusting said teeth and permitting the same to revolve independently of said adjusting means; but it will be apparent to one skilled in the art that the frame-bars may be rigidly secured together without the interposition of tooth-supports between said bars and that the teeth may be supported by other forms of tooth-supports permitting of the desired movement of said teeth, and consequently I do not herein limit my invention to the described construction and arrangement of said parts. It will also be evident that the particular construction of the adjusting means described herein may be considerably varied without departing from the spirit of my invention—as, for instance, the tooth-supports may be provided with independent adjusting means detachably connected thereto, or only a part of the tooth-supports carried by a single section may be connected together and simultaneously adjusted; but, providing said adjusting means is so constructed as to adjust the tooth-support and to permit the tooth-support to revolve independently thereof, the same is no departure from my present invention, and consequently I do not herein limit myself to the exact construction and arrangement of the adjusting means for the teeth.

Having thus fully described my invention, what I claim as new, and desire to secure by Letters Patent, is—

1. A harrow comprising a frame having openings therein, teeth automatically revolvable in said openings while the harrow is in motion, and means detachably connected to said teeth for holding the same in operative position, and for releasing the same and permitting their automatic revolvable movement in said openings independently of said means, substantially as and for the purpose described.

2. A harrow comprising a frame, a tooth-support mounted on the frame and automatically revolvable while the harrow is in motion, and adjusting means detachably connected to said support, for adjusting the position thereof, for holding the support in operative position, and for releasing the same and permitting its automatic revolvable movement independently of said means, substantially as and for the purpose specified.

3. A harrow comprising a frame, a tooth-support, an adjusting means having a locking member for connecting said support to the adjusting means and having a shoulder for engaging the frame as the adjusting means is operated and automatically disconnecting said locking member from the tooth-support, whereby the tooth-support is adjusted by said means and is permitted to automatically revolve independently of said means while the harrow is in motion, substantially as and for the purpose set forth. 60
4. A harrow comprising a frame, teeth supported by the frame and automatically revolute while the harrow is in motion, and an adjusting-frame arranged above the former frame, and detachably connected to said teeth for adjusting the position thereof, for holding the teeth in operative position, and for releasing the same and permitting their automatic revolute movement independently of said adjusting-frame, substantially as and for the purpose specified. 65
5. A harrow comprising a frame, tooth-supports pivoted to the frame and automatically revolute while the harrow is in motion, and an adjusting-frame arranged above the former frame and provided with depending arms pivoted to the frame and movable independently of the tooth-supports, said arms being detachably connected to the tooth-supports for adjusting the position of the tooth-supports, for holding said supports in operative position, and for releasing the same and permitting their automatic revolute movement independently of the adjusting-frame, substantially as and for the purpose set forth. 70
6. In a harrow, the combination of a draft-frame having openings therein, teeth movable in said openings and tooth-supports for the teeth; with adjusting means comprising an adjusting-frame above the former frame, locking members for detachably connecting the adjusting-frame to the tooth-supports, whereby the tooth-supports are adjusted or are permitted to automatically revolve independently of the locking members, said locking members being provided with shoulders for engaging the draft-frame and preventing derangement of the locking members during the independent movement of the tooth-supports, and a lever connected to said adjusting-frame for operating the same, substantially as and for the purpose described. 75
7. A harrow comprising a frame, teeth supported by the frame and automatically revolute while the harrow is in motion, movable locking members normally connected to the teeth for adjusting the teeth and holding the same in their operative position, and means for disconnecting the locking members from the teeth and permitting automatic revolute movement of the teeth independently of the locking members, substantially as and for the purpose specified. 80
8. In a harrow, the combination of a tooth-support having a bearing-face and a cut-out above said face, a clip-plate beneath said face having an upwardly-extending arm provided in a shoulder engaged with the cut-out, a tooth passed between the face and clip-plate, and a clamp for securing the foregoing parts together, substantially as and for the purpose set forth. 85
9. In a harrow, the combination of a movable tooth-support, an adjusting-arm having a guideway therein, a locking member movable in the guideway for engaging the tooth-support, and a spring for forcing said locking member to operative position, substantially as and for the purpose described. 90
10. In a harrow, the combination of a frame, a movable tooth-support, an adjusting-arm having a guideway therein, a locking member movable in the guideway for engaging the tooth-support and provided with a shoulder for engaging the frame and forcing said locking member from operative position, and a spring for forcing said locking member to operative position, substantially as and for the purpose specified. 95
11. In a harrow, the combination with a movable adjusting-frame, a lever for operating said frame, and a connecting-plate C³ hinged to the frame and formed with substantially parallel shoulders for engaging the lever, substantially as and for the purpose set forth. 100
12. In a harrow, the combination with a movable adjusting-frame, a lever for operating said frame, a connecting-plate C³ hinged to the frame and formed with substantially parallel shoulders for engaging the lever, and a clip-plate C⁵ secured to said frame and formed with a shoulder C⁶ for engaging the connecting-plate, substantially as and for the purpose described. 105

In testimony whereof I have hereunto signed my name, in the presence of two attesting witnesses, at Syracuse, in the county of Onondaga, in the State of New York, this 12th day of September, 1893.

HIRAM M. BURDICK.
